Primary Examiner — Wendy L Arminio(74) *Attorney, Agent, or Firm* — Breiner & Breiner, L.L.C.(57) **CLAIM**

The ornamental design for a pour spout, as shown and described.

DESCRIPTION

FIG. 1 is a front and side perspective view of a pour spout.

FIG. 2 is a top view of the pour spout of FIG. 1;

FIG. 3 is a bottom view of the pour spout of FIG. 1;

FIG. 4 is a first side view of the pour spout of FIG. 1;

FIG. 5 is a second side view of the pour spout of FIG. 1; and,

FIG. 6 is a perspective view of the pour spout of FIG. 1 in an environment of use.

The broken lines in FIG. 6 illustrating a container and lid depict environment and form no part of the claimed design.
